DESIGN FOR A COMBINED CLOCK CASE
AND DIAL

Pierre J. Godart, New York, N. Y., assignor to
The United States Time Corporation, Water-
bury, Conn., a corporation of Connecticut

Application November 15, 1946, Serial No. 134,813

Term of patent 14 years

(Cl. D42—7)

To all whom it may concern:

Be it known that I, Pierre J. Godart, a citizen of the United States, residing in New York, in the county of Manhattan and State of New York, have invented a new, original, and ornamental Design for a Combined Clock Case and Dial, of which the following is a specification, reference being had to the accompanying drawing, forming a part thereof.

In the drawing:

Fig. 1 is a front elevational view of a combined clock case and dial showing the essential features of my design in full lines.

Fig. 2 is a top plan view of the disclosure in Fig. 1.

The principal feature of the design is the floral arrangements on both the bezel of the combined clock case and the dial of the clock.

I claim:

The ornamental design for a combined clock case and dial, as shown and described.

PIERRE J. GODART.
